CLAIM

We claim the ornamental design for a display screen or portion thereof with graphical user interface for water delivery components, as shown and described.

DESCRIPTION

The FIGURE is an exploded front view of the display screen or portion thereof with graphical user interface for water delivery components, according to our new design.

In the drawings, the dot-dash broken lines are for the purpose of illustrating the display screen. The dash-dash broken lines are for the purpose of illustrating environmental structure (the water delivery component) and portions of the graphic user interface. No subject matter shown in either the dot-dash broken lines or dash-dash broken lines form a part of the claimed design.
